[57] CLAIM

The ornamental design for a vehicle light mounting bracket, as shown and described.

DESCRIPTION

FIG. 1 is a top, front, left hand side perspective view of a vehicle light mounting bracket showing my new design;

FIG. 2 is a left hand side elevational view thereof on an enlarged scale, the right hand side being a mirror image;

FIG. 3 is a rear elevational view thereof;

FIG. 4 is a front elevational view thereof;

FIG. 5 is top plan view thereof;

FIG. 6 is a bottom plan view thereof;

FIG. 7 is a top, front perspective view thereof on a reduced scale, the light and the fragmentary vehicle being shown in broken lines for illustrative purposes only.
